UNITED STATES PATENT OFFICE

WILLIAM C. HIERING, OF NEWARK, NEW JERSEY, ASSIGNOR TO J. E. MURGOTT COMPANY, OF NEWARK, NEW JERSEY, A CORPORATION OF DELAWARE

HAND BAG

Application filed October 6, 1928. Serial No. 310,718.

This invention relates to hand bags and more particularly to devices designed to facilitate the carrying of such bags.

The usual handbag for ladies is provided with a strap by means of which the bag may be swung at the side of the user. This manner of carrying handbags has been found objectionable in that the bag hanging at the side of the user is capable of being easily manipulated by pickpockets without attracting attention. Also, it has been found inconvenient and uncomfortable to carry. As a result, women generally carry such bags by grasping an end of the bag with the palm of the hand and holding the bag between the body and the arm. When carried in such a manner, it is obvious that the strap is superfluous.

Another popular expedient is the provision of a band having its ends attached to the side of the bag so that a hand may be inserted between the bag and the strap. While this type of bag may be conveniently carried, the acidity of users' hands in constantly grasping the metal frame, results in tarnishing of the latter, such frames usually being gold plated or silver plated. Obviously, tarnishing of the frame affects the appearance of the bag, since such bags are designed for ornamentation as well as utility.

In view of the present tendency of women to carry bags by grasping one end of the bag by the hand and holding the bag between the body and the arm, it is an object of this invention to provide a device which will facilitate the carrying of bags in such a manner.

A further object is the provision of a bag carrying device which will have ornamental characteristics as well as utility, and thus assist in the sale of bags upon which it is employed.

These and other objects, which will become apparent as the description progresses, are accomplished by the novel construction, combination and arrangement of parts, herein-after described and illustrated in the accompanying drawings, forming a material part of this disclosure, and in which:—

Figure 1 is a view showing the device applied to a bag frame.

Figure 2 is a view showing the device applied to a frameless bag.

Figure 3 is a cross-sectional view showing the manner in which the device is attached to a bag frame.

Figure 4 is a cross-sectional view showing the manner in which the device is attached to a frameless bag.

Figure 5 is a perspective view showing the manner in which the device is used for carrying a handbag.

Referring to Figure 1, a bag frame member 8 is held to a similar member (not shown) by means of a bag fastener 9, this structure being common in handbags. Mounted on the member 8 is a stud 10 having a pin projecting downwardly through the member 8, the end of the pin being split to form brads 11 and 12 to securely hold the stud to the frame member. A pin 13 projects upwardly from the stud 10 and rotatably mounted upon the pin 13 is a head 14 having recesses 15 and 16 to pivotally receive the ends 17 and 18 of a resilient finger grip 19 which in the present case is ring-shaped. The pin 13 is flattened at its head 20 to prevent removal of the head 14 therefrom.

In Figure 5 is shown the manner in which the bag is carried.

As will be seen, the thumb is passed through ring 19 while the remaining fingers of the hand grasp the end of the bag nearest the ring. The bag may be held between the arm and the body; or may be held beside the body of the user. In any case, the thumb passing through the ring 19 and the fingers grasping the end of the bag, enable the latter to be securely and conveniently carried.

In Figures 2 and 4, is shown the manner in which the device is applied to a frameless bag. A shield 21 of any desired shape, has its edges bent over a plate 22 the latter having integral projecting brads 23 and 24 which pierce the flexible material 25 of the bag and pass through apertures in a protecting plate 26, the brads being bent over the plate 26 to securely hold the parts together.

A stud 27 swivelly supporting a head 28

and finger grip 29, is attached to the shield 21 and plate 22 by means of structure similar to that described above in connection with Figures 1 and 3. The bag in this case 5 may be obviously carried in the same manner as described above.

It is apparent that the finger grip may be of any desired shape or it may take the form of a leather loop; in any event the fundamental object is the provision of means to receive the thumb so that the remaining fingers of the hand may grasp the body portion of the bag.

From the above description it will be seen 15 that there has been presented a bag carrying device which not only is of great utility, but in addition has striking ornamental characteristics. It is obvious that the device enables the carrying of a hand-bag more securely than heretofore has been the case, and obviates the necessity of grasping the metal frame work of the bag with the resulting tarnishing and corroding effects.

Although the foregoing is descriptive of 25 the preferred embodiment of the invention, it will be apparent that minor changes may be made in its construction, without the exercise of invention or conflicting with the scope of the claims hereto appended.

30 Having thus described my invention, what I claim to be new and desire to secure by Letters Patent is:

1. In combination with a frameless handbag made of flexible material, a protecting 35 plate at the inner side of the handbag material, a shield on the outer side of said material, means for rigidly connecting said plate and shield, a head swivelly secured to said shield, said head being provided with recesses and a ring pivoted in the recesses in the head, said ring being adapted to receive the thumb of a hand and to be pivoted and swivelled to accommodate the movement 40 of the thumb and enable the other fingers of 45 the hand to freely grasp the material of the bag.

2. In combination with a handbag, a shield secured to the outer side of the handbag material, a head swivelly secured to said shield, 50 said head being provided with recesses, and a ring pivoted in the recesses in the head, said ring being adapted to receive the thumb of a hand and to be pivoted and swivelled to accommodate the movement of the thumb 55 and enable the other fingers of the hand to freely grasp the material of the bag.

This specification signed this 2nd day of October, 1928.

WILLIAM C. HIERING.
